DESIGN FOR A SERVING BASKET

James D'Arcy, Oakland, Calif.

Application February 5, 1940, Serial No. 90,024

Term of patent 7 years

To all whom it may concern:

Be it known that I, James D'Arcy, a citizen of the United States and a resident of Oakland, county of Alameda, State of California, have invented a new, original, and ornamental Design for a Serving Basket, of which the following is a specification, reference being had to the accompanying drawing, forming part thereof.

I claim:

The ornamental design for a serving basket, substantially as shown.

JAMES D'ARCY.
